UNITED STATES PATENT OFFICE.

WILLIAM H. KELL, OF CHICAGO, ILLINOIS, ASSIGNOR TO SHEA SMITH & COMPANY, OF CHICAGO, ILLINOIS.

BINDER-BAR FOR FILES.

SPECIFICATION forming part of Letters Patent No. 717,412, dated December 30, 1902.

Application filed September 9, 1902. Serial No. 122,659. (No model.)

To all whom it may concern:

Be it known that I, WILLIAM H. KELL, a citizen of the United States, residing at Chicago, in the county of Cook and State of Illinois, 5 have invented certain new and useful Improvements in Binder-Bars for Files, of which the following is a specification.

The object of this invention is to provide a simple and easily-regulated locking mechanism adapted to hold the contents of the file against displacement and capable of being easily unlocked and removed and allow access to the file for the purpose of adding thereto or subtracting therefrom.

15 A further object of this invention is to provide a mechanism which will lock and unlock both of the filing-pins simultaneously; and the invention consists in the features of construction of parts hereinafter described and 20 claimed.

In the drawings, Figure 1 is an end elevation of an ordinary letter-file, showing the binder-bar in position. Fig. 2 is a top or plan view of a letter-file, partly broken away. Fig. 25 3 is a bottom view of the binder-bar and mechanism therein contained in unlocked relation; Fig. 4, a similar view to Fig. 3, showing the parts of the bar in locked relation and the protecting-blocks removed; and Fig. 5 a longitudinal sectional view of Fig. 3.

30 As shown, the locking-bar is arranged in position on a letter-file consisting of a stiff lower board or cover A and a hinged upper board or cover A', the latter consisting of a fixed section a and a hinged section a', connected, by means of a hinge a², in the usual manner, and between the upper and lower boards or covers are arranged the letters, orders, or other files to be preserved or filed. 35 The locking-bar, which more particularly forms the subject-matter of this invention, is arranged to lie outside of and in longitudinal relation to the fixed section a of the upper cover and is composed of an upper plate, oblong in form, which may be made of metal or other suitable material and is provided with two holes b for the passage therethrough of filing pins or studs B', which are fixedly attached to and extend upward from the lower 40 board or cover through the letters, orders, or other files inserted between the covers and

through the fixed section a of the upper board or cover and finally through the binder-bar. Fixedly attached to the under face of the plate are guide-blocks C and c, two in number, as 55 shown, and arranged adjacent to the holes b in the upper plate. Each of these guide-blocks is provided with two longitudinally-extending holes for the passage therethrough of locking-rods C', which are united together 60 at one end by means of a head c', the inner face of which when in unlocked relation is in alignment with the outer edge of the hole contiguous therewith, while the opposite ends of the rods are united by means of a 65 cross-head D, into which the ends of the rods are inserted and held by means of pins d or otherwise. Slidably mounted on the two rods and normally in contact with the cross-head D, which unites the ends of the locking-rods, 70 is a sliding locking-block D', which is adapted to travel toward and from the hole in the plate and when advanced to the position shown in Fig. 4 to contact with the filing pin or stud inserted therein and by the pressure 75 exerted against the filing pin or stud by means of the locking-block to unite or lock the bar against removal from the filing pins or studs. The cross-head D is provided with an interior screw-thread, and the locking-block D' is also provided with an interior 80 screw-thread in opposite relation to the screw-thread in the cross-head. Screw-threaded into and through the cross-head is an adjusting-screw E, which is provided with normal 85 screw-threads e, which engage with the screw-threads in the cross-head, and is further provided on its inner end with oppositely-turned screw-threads e', which engage with the screw-threads in the locking-block, causing 90 the locking-block and the cross-head to be oppositely moved as the adjusting-screw is turned, thereby drawing back the locking-rods and causing the space between the locking-block and the head connecting the two 95 rods to be diminished, by which means the locking-block and the head are brought into tight contact with the two pins or studs and lock the entire bar against removal. The adjusting-screw is provided on its outer or 100 free end with a squared head for the insertion thereon of a key for turning the adjust-

ing-screw, and the end of the screw is held against lateral movement by means of a recessed guide-plate E', which is secured to the plate B by means of pins e³ or otherwise.

- 5 In order to protect the locking mechanism from injury either by bending or by the admission of dirt thereinto, protecting-blocks F, F', and F² are inserted in the spaces between the guide-blocks, the blocks F and F' being recessed to allow space for the operation of the locking mechanism and the block F² preferably consisting of two sections, although a single recessed block would perform the same function. The blocks are of a thickness to lie flush with the lower faces of the guide-blocks C, c, and E'.

In use the letters, orders, or files to be preserved are inserted in place on the filing-pins in the usual manner, and the upper cover is then brought down in place thereon, after which the pins are inserted through the holes in the locking-bar and the latter is firmly locked onto the pins by means of the movement of the adjusting-screw, as heretofore described. It will thus be seen that a single movement serves to lock the bar to both of the filing-pins, that the mechanism is simple and readily adjustable, and that the parts are so inclosed and protected as to be free from the danger of injury.

What I regard as new, and desire to secure by Letters Patent, is—

1. In a locking-bar, the combination of a plate having therein holes for the passage therethrough of filing-pins, locking-rods connected at their rear ends and slidably mounted in relation to the plate, a locking-block slidably mounted on the rods, and means for simultaneously moving the rods and the block in opposite relation, substantially as described.

2. The combination of a plate having therein holes for the passage therethrough of filing-pins, locking-rods connected at their rear ends and slidably mounted in relation to the plates, a locking-block slidably mounted on the rods and provided with interior screw-threads, an adjusting-screw threaded into the locking-block, and means for holding the screw in coacting relation, substantially as described.

3. In a locking-bar, the combination of a plate having therein holes for the passage therethrough of filing-pins, guide-blocks attached to the under face of the plate, locking-rods connected at their rear ends and

slidably mounted within the guide-blocks, a locking-block slidably mounted on the rods and provided with interior screw-threads, an adjusting-screw threaded into the locking-block, and means for holding the screw in coacting relation, substantially as described.

4. In a locking-bar, the combination of a plate having therein holes for the admission therethrough of filing-pins, an adjusting-screw provided with oppositely-arranged screw-threads, locking-rods, slidably mounted and connected at their rear ends, a locking-block having therein a screw-thread and slidably mounted on the locking-rods, and a cross-head having interior screw-threads in opposite relation to the screw-threads in the locking-block and adapted to travel in opposite relation thereto upon the rotation of the adjusting-screw, substantially as described.

5. In a locking-bar, the combination of a plate having therein holes for the passage therethrough of filing-pins, parallel locking-rods united at one end and connected at their other ends by means of a cross-head having therein interior screw-threads, guide-blocks for the movement therethrough of the locking-rods, a locking-block slidably mounted on the locking-rods, and having interior screw-threads in opposite relation to the screw-threads in the cross-head, and an adjusting-screw having opposite screw-threads for engagement with the opposite screw-threads of the cross-head and the locking-block, substantially as described.

6. In a locking-bar, the combination of a plate having therein holes for the passage therethrough of filing-pins, parallel locking-rods united at one end and connected at their other ends by means of a cross-head having therein interior screw-threads, guide-blocks for the movement therethrough of the locking-rods, a locking-block slidably mounted on the locking-rods, and having interior screw-threads in opposite relation to the screw-threads in the cross-head, an adjusting-screw having opposite screw-threads for engagement with the opposite screw-threads of the cross-head and the locking-block, and protecting-blocks inserted between the guide-blocks, substantially as described.

WILLIAM H. KELL.
